ELECTRICALLY POWERED MEAT GRINDER

Daniel E. McCue, Santa Barbara, Calif., assignor to
Rival Manufacturing Company, Kansas City, Mo.

Filed Dec. 3, 1973, Ser. No. 420,949

Term of patent 14 years

Int. Cl. D7—04; D15—08
U.S. Cl. D55—1 B

Fig. 1.

Fig. 2.

Fig. 3.

Fig. 4.

Fig. 5.

FIG. 1 is a perspective view of an electrically powered meat grinder showing my new design;

FIG. 2 is an enlarged side elevational view of the meat grinder shown in FIG. 1;

FIG. 3 is a top plan view of the meat grinder shown in FIG. 2;

FIG. 4 is a left hand end elevational view of the meat grinder shown in FIG. 2; and

FIG. 5 is a right hand end elevational view of the meat grinder shown in FIG. 2.

I claim:

The ornamental design for an electrically powered meat grinder, as shown and described.
